(57) **CLAIM**

The ornamental design for a heart compressor with and without a cup, as shown and described.

DESCRIPTION

FIG. 1 is a bottom perspective view of the heart compressor according to the invention;

FIG. 2 is a front perspective view of the heart compressor;

FIG. 3 is a front view of the heart compressor;

FIG. 4 is a top view of the heart compressor;

FIG. 5 is a bottom view of the heart compressor;

FIG. 6 is a view from one side of the heart compressor;

FIG. 7 is a view from the other side of the heart compressor;

FIG. 8 is a bottom perspective view of the heart compressor, without a cup;

FIG. 9 is a front perspective view of the heart compressor, without a cup;

FIG. 10 is a front view of the heart compressor, without a cup;

FIG. 11 is a back view of the heart compressor, without a cup;

FIG. 12 is a view from one side of the heart compressor, without a cup;

FIG. 13 is a view from the other side of the heart compressor, without a cup;

FIG. 14 is a top view of the heart compressor, without a cup;

and,

FIG. 15 is a bottom view of the heart compressor, without a cup.
